TO GOODYEAR'S INDIA RUBBER GLOVE MANUFACTURING COMPANY, A CORPOR-
ATION OF CONNECTICUT.

DEVICE FOR MOLDING HOLLOW ARTICLES.

1,188,693.

Specification of Letters Patent. Patented June 27, 1916.

Application filed September 1, 1915. Serial No. 48,417.

To all whom it may concern:

Be it known that we, ERASMIUS STAHL and WILHELM KLEIN, citizens of the United States, residing at Naugatuck, county of New Haven, State of Connecticut, have invented certain new and useful Improvements in Devices for Molding Hollow Articles, of which the following is a full, clear, and exact description.

10 Our invention relates particularly to cores for molding hollow articles having a small opening or neck leading to the interior thereof, such as hot-water bottles and similar articles made of rubber.

15 The object of our invention is to provide a core for such articles that can be easily removed through the neck or other small opening without, injuring the articles and one that is simple and easily manipulated

20 for use in the molding process.

For a detailed description of one form of our invention, reference may be had to the following specification and to the accompanying drawing forming a part thereof, in

25 which:

Figure 1 is a side elevation of our improved core and showing a hot water bag inclosing the same, in section; Fig. 2 is a plan view of one of the core sections; Fig. 3 is a transverse sectional view of the neck of the bottle showing the manner of removing the first section of the core; Fig. 4 is a longitudinal sectional view of the same; and Fig. 5 is a side view of a modification of

35 the core.

Referring to the drawing, the numerals 1 to 10 inclusive represent the successive sections of the core in the shape of rectangular bars with rounded ends, as indicated in Fig. 2. These are connected together and with the neck section of the core by a rod 13 passing centrally through each of the sections and being fastened to the first section 1 by being screw-threaded as at 14. The rod projects sufficiently far beyond the core sections to enter a hole at the outer mold sections and forms a dowel pin which serves to center the lower end of the core within the mold recess, as indicated at 15. The rod 13 is also provided at its upper end with a limiting flange 16 and a suitable finger pin 17.

The neck section 11 is provided with a cylindrical portion 12 upon which the screw-threaded ring 18 is placed when the core 55 is being assembled so that said ring will be embedded in the neck of the bottle when it is molded.

The core sections are provided with means for keeping the same in register with each other, such as the dowel pins 19.

The outer mold sections are provided with a recess in which a nipple 20 is formed, which, when the bottle is completed, is adapted to contain a suitable connecting 65 piece to permit the attaching of a rubber tube so that the bottle may also be used as a pressure reservoir for a fountain syringe. It is obvious that instead of the nipple 20, the usual tab for the water bottle may be 70 molded at its lower end.

Fig. 5 shows the core sections with slightly rounded corners which form small ridges on the inner surface of the bottle, thereby strengthening the walls thereof and at the 75 same time obviating any nicking or uneven wearing of the said corners.

The core is utilized in the following manner: The sections of the core having been assembled and fastened together by the rod 80 13, the two halves of the mold cavity are lined with suitable calendered sheet stock, the core inserted and the mold sections closed upon each other and clamped in position in any well known way. The article 85 is then cured in any suitable manner. When the mold has been removed from the vulcanizer and sufficiently cooled, the article and its contained core are removed from the mold sections and the rod 13 withdrawn. 90 This frees the neck section 11 of the core. The bag or other article is then slightly stretched until one end of the section 10 can enter the ring 18, after which said section 10 may pass through the ring as indicated in Figs. 3 and 4, and thus entirely removed. The succeeding core sections 9, 8, 7, etc. are then removed in a similar manner, after which the article is ready for trimming and finishing.

Having thus described this form of our invention, we do not wish to be understood as being limited to the details of forms and arrangement of parts set forth, nor do we

wish to be understood as being limited to the manufacture of water bottles, for various hollow articles having a small neck or opening may be advantageously manufactured in the same manner.

What we claim and desire to protect by Letters Patent is:

1. A mold for hollow articles comprising, a core made of sections arranged transversely to and adapted to pass through the opening in the article and locking means for holding said sections together centrally, said means being adapted to pass through said opening to engage said sections and lock the same together transversely.
15. 2. A mold for hollow articles comprising, a core made of sections arranged trans-

versely to and adapted to pass through the opening in the article and locking means adapted to draw said sections together transversely and operated through, and located in alignment with, said opening.

3. A mold for hollow articles comprising, a core including bars, extending transversely to and adapted to pass through the opening in said articles and a rod extending through said sections and through said opening and having screw-threaded engagement with one of said sections, whereby the latter are drawn together into interlocking engagement.

Signed this 15th day of October, 1915.

ERASMUS STAHL
WILHELM KLEIN.
